UNITED STATES PATENT OFFICE.

WALTER A. STATTMANN, OF TOLUCA, CALIFORNIA, ASSIGNOR OF TWO-FIFTHS TO RANDOLPH C. CURRY AND JOSEPHINE S. EVANS, OF TOLUCA, AND THOMAS E. DILLEY, OF LOS ANGELES, CALIFORNIA.

NON-REFILLABLE BOTTLE.

SPECIFICATION forming part of Letters Patent No. 779,380, dated January 3, 1905.

Application filed July 11, 1904. Serial No. 216,115.

To all whom it may concern:

Be it known that I, WALTER A. STATTMANN, a citizen of the United States, residing at Toluca, in the county of Los Angeles and State of California, have invented new and useful Improvements in Non-Refillable Bottles, of which the following is a specification.

The object of my invention is to provide a stopper for a bottle that cannot be removed from the neck thereof except by breaking the bottle or destroying the stopper; and the object of my invention is to prevent the reuse of a bottle. I accomplish this object by means of the device described herein and shown in the accompanying drawings, in which—

Figure 1 is a central vertical section of the neck of a bottle with my improved stopper therein. Fig. 2 is a detailed view of my attachment for a cork, slightly modified.

In the drawings, A represents the neck of the bottle, and B represents my device for attachment to the cork. This attachment consists of the body portion C, cylindrical in form, carrying in the interior thereof a spiral spring D, the lower end of the spring being secured to a rivet secured to the cylinder. On the upper end of the spiral spring is mounted the saucer-shaped stopper F, resting upon the upper end of the cylinder and having an air-tight fit thereon. This stopper will be spring-pressed against the cylinder and will prevent the passage through the cylinder downwardly into the bottle of any liquid, but will permit the passage out of the bottle of any liquid

that may be contained therein. Disposed above the stopper and surrounding the upper portion of the cylinder is the housing G, arranged, as shown in Fig. 1, to prevent access from the outside to the stopper F, so as to prevent the stopper F from being raised from its seat on the cylinder, and thereby prevent anybody from elevating it or in any manner tampering with it in order to pass any liquid into the interior of the bottle. On top of the housing I have provided a protecting cap or shield H, which completely covers the opening G' in the top of the housing.

My improved cork is prepared for use as follows: The cork I has a central bore therethrough, into which the cylinder C is passed, as shown in Fig. 1, the lower end of which projects slightly beyond the lower end of the cork, and when in this position on the lower end of the cylinder is formed a flange C' by any suitable means which will prevent the cylinder from being removed from the cork. The cork is of a diameter larger than the cavity A' in the neck of the bottle. This cavity is provided with two annular grooves A'', extending outwardly therefrom, and when the cork is placed into the neck of the bottle after having my sealing attachment secured thereto it is firmly crowded down upon the shoulder A''' at the bottom of the cavity A'. This will cause the cork to expand and fill up the annular grooves A'', the cork having been previously steamed, making it resilient and well adapted to fit into the cavity A', and it will completely fill the annular grooves A'' therein.

When a cork properly steamed with my device thereon is placed in a bottle having a neck such as shown and described it will prevent the passage thereinto of any liquid, but will permit any liquid therein to pass out upon inverting the bottle, the usual cork J being removed therefrom.

Having described my invention, what I claim as new, and desire to secure by Letters Patent, is—

1. In a non-refillable bottle; a bottle provided with a neck having a cavity therein larger than the neck provided with annular grooves therein, in combination with a cork provided with an attachment herein shown, consisting of a cylinder having on its upper end a stopper and a housing for said stopper and a spiral spring secured in the lower end of said cylinder substantially as herein shown and described.

2. In a non-refillable bottle having an opening in the neck thereof of a uniform diameter except as to the cork-receiving cavity; a cork-receiving cavity in said neck of a larger diam-

eter than the bore of the neck, and having annular grooves surrounding said cavity extending outwardly therefrom.

3. The herein-described means to prevent
5 the filling of a bottle having an annular recess
in the neck thereof after the same is corked,
the said recess being provided with annular
grooves therein, the said means consisting of
a cork having a central bore therethrough; a
10 cylinder in said bore having on its upper end
a stopper, a spiral spring in said cylinder

secured to the lower end thereof and attached
to said stopper and adapted to hold said stopper
in spring-pressed engagement with the top
of the cylinder.

15

In witness that I claim the foregoing I have
hereunto subscribed my name this 24th day
of June, 1904.

WALTER A. STATTMANN.
